UNITED STATES PATENT OFFICE.

MATTHIAS N. FORNEY, OF NEW YORK, N. Y.

FLUID-PRESSURE ENGINE.

SPECIFICATION forming part of Letters Patent No. 735,741, dated August 11, 1903.

Application filed August 8, 1902. Serial No. 118,969. (No model.)

To all whom it may concern:

Be it known that I, MATTHIAS N. FORNEY, of the borough of Manhattan, in the city and State of New York, have invented a certain 5 new and useful Improvement in Fluid-Pres-
sure Engines, of which improvement the fol-
lowing is a specification.

My present invention is an improvement on that set forth in Letters Patent of the United 10 States No. 489,648, granted and issued to me under date of January 10, 1893, and is more particularly designed for application to com-
pound steam-engines, but is applicable to other fluid-pressure and to binary engines 15 which are not compound; and its object is to facilitate and further improve the means whereby the reciprocating elements of engines of such character are made to counter-
balance each other by a more convenient dis-
20 position of their parts, which results in a re-
duction of cost of the engines, and, further, by locating one cylinder within the other, so that the axes of the two cylinders are coinci-
25 dent. The centers of gravity of their two pistons then both traverse this axis, and thus the disturbing action caused by their move-
ment in two different planes is avoided.

The improvement claimed is hereinafter fully set forth.

30 In the compound engine set forth in Letters Patent No. 489,648 aforesaid the piston-rod of the low-pressure cylinder is directly connected to what is termed a "primary" lever, which is in turn articulated to a pair of "sec-
35 ondary" levers, which oscillate in journals or trunnions supported in fixed bearings, the system of levers forming a "parallel" motion which constrains the piston-rod to move in a straight line. In this construction the axes 40 of the journals or trunnions of the secondary levers are in a plane which coincides with the axis of one of the cylinders, which is the line in which the center of its piston-rod moves. The piston-rod of the high-pressure piston is 45 connected to the lower end of the secondary lever; but as these move in a path which is an arc of a circle to secure rectilineal move-
ment of this piston-rod it requires to be and is shown as connected to the levers by means 50 of a guide, cross-head, and short links. The other two cylinders are located with their axes in two planes some distance apart, and

consequently the movement of the pistons in opposite directions to each other exerts a turning action in the mechanism, which to a 55 certain extent is a source of disturbance. Under my present invention the axes of the two cylinders are made coincident with each other by locating one cylinder within the other, the outer one surrounding the inner 60 one. The piston-rods of each cylinder are then connected to separate primary levers which are articulated to opposite ends of a pair of secondary levers, so that all the piston-rods are constrained to move in straight 65 lines. By this means the guides, cross-head, and short connecting-links of Patent No. 489,648 are wholly dispensed with, and as the centers of gravity of the two pistons move in the same line no turning action or consequent 70 disturbance is exerted thereby.

In the accompanying drawings, Figure 1 is a vertical transverse central section through a vertical two-cylinder compound engine of the overhead marine type, illustrating an 75 embodiment of my invention, the cylinders being located one within another about a common axis; Fig. 2, a vertical longitudinal central section through the same; and Fig. 3, a horizontal section on the line *c d* of Figs. 80 1 and 2, the oscillating levers being shown in a horizontal position and in elevation in Fig. 3.

The drawings illustrate the application of my invention in a compound engine of the vertical overhead marine type, although it 85 will be obvious that the cylinders may be located horizontally or in an inclined position, if desired. It will be understood, as has already been explained, that if the pistons of two cylinders which are in different planes 90 are connected to a system of oscillating levers, so that the pistons move in relatively oppo-
site directions, their opposite movements will exert a turning action on the mechanism, which is to a certain extent a source of disturbance. This may to a very considerable 95 extent be compensated by the employment of a supplemental counterweight, as set forth in Letters Patent of the United States No. 701,477, granted and issued to me under date 100 of June 3, 1902, but can be completely eliminated by the construction herein shown, in which the high-pressure cylinder 1^a is surrounded by an annular low-pressure cylinder

1, the axes of the two cylinders being therefore coincident. The centers of gravity of the pistons consequently traverse in the same straight line, and therefore when moving in opposite directions they do not exert any turning action on the mechanism or produce the disturbance before referred to. In order that the pistons may move in opposite directions, they are connected with the connecting-rod and crank-pin through the intermediation of an oscillating-lever system, the detailed features of which mechanism will now be explained. The high-pressure cylinder 1^a and the low-pressure cylinder 1, which surrounds and axially coincides with the high-pressure cylinder, are secured to housings or standards 55, fixed upon a bed-plate 56, which supports the main bearing of the crank-shaft 19 of the engine. The high-pressure cylinder is fitted with a piston 2^a of the usual form, which is fixed upon a piston-rod 3^a, to the outer end of which is secured a forked head 48, which is coupled by a pin 15^a to the inner arms of a pair of primary levers 7 7, these being two parallel lever-bars. The outer arms of the primary levers 7 7 are coupled by a pin 9 to a pair of radius-links 11 11, the opposite ends of which are coupled to a pin 10, fixed to the low-pressure cylinder. The low-pressure cylinder 1 is fitted with an annular piston 2, which is fixed upon two piston-rods 3 3, projecting through suitable stuffing-boxes and having their outer ends coupled by pins 15 15 to the inner arms of a pair of second primary levers 7^a 7^a. The outer arms of the second primary levers 7^a are, similarly to those of the primary levers 7, coupled by a pin 9^a to a pair of radius-links 11^a 11^a, the opposite ends of which are coupled to a pin 10^a, fixed to the low-pressure cylinder. The primary levers 7 and second primary levers 7^a are coupled intermediately of their ends to a pair of secondary levers 8 8, which are parallel lever-bars having central journals 13 fitting in fixed bearings 14, the swiveling connection of the secondary levers to the primary levers 7 being effected by a pin 12 and that to the second primary levers by a pin 12^a. The main connecting-rod 4 is coupled at its upper end to the forked head 48 of the high-pressure piston-rod and to the primary levers 7 by the pin 15^a, and its lower end is coupled to the crank-pin 18 of the crank-shaft 19. The operation of the high-pressure piston, piston-rod, and connecting-rod is similar to that of the corresponding parts in engines of the ordinary construction; but the piston-rods are constrained to move in straight lines by the system of oscillating levers, which constitutes a parallel motion. The low-pressure piston being connected by its two piston-rods to the second primary levers 7^a, the pressure exerted upon it is transmitted by said levers to the secondary levers 8 8, and by them to the primary levers 7 7, and thence to the forked head 48, connecting-rod 4, and

crank-pin 18. The levers are so proportioned that the inner ends of the primary levers and second primary levers move in substantially straight lines, and these levers serve as guides for the piston-rods of both the high and the low pressure cylinders.

The inner high-pressure cylinder 1^a is made separate from the outer low-pressure cylinder 1 and is attached to the lower cylinder-head 49^a by a flange 52. In order to allow for expansion and contraction and any unequal length of the two cylinders, the inner cylinder is attached to the upper cylinder-head 49 by a joint provided with packing 50, which allows the inner cylinder to move lengthwise independent of the outer cylinder and its head. The head 51 of the inner cylinder has a ring 53 formed on its under side, which acts as a gland to compress the packing 50, and thus makes a steam-tight joint between the inside cylinder and the cylinder-head 49.

The means for admitting motive fluid to the central high-pressure cylinder and conducting it thence to the low-pressure cylinder after it has exerted its pressure on the high-pressure piston and finally exhausting it from the low-pressure cylinder after it has been expanded and done its work therein consists in valves and ports and passages of special construction. These constitute the subject-matter of a separate application filed by me of even date herewith, Serial No. 118,970.

An annular supply-passage 20 is formed around the outside of the low-pressure cylinder 1, said passage communicating directly and continuously with the supply-pipe 20^a, leading from the source of fluid-pressure and having at its ends supply-ports 21 21^a, which open into the low-pressure cylinder, but which are continuously cut off from communication therewith by valves. (Not shown in the drawings.) The supply-passage entirely surrounds the low-pressure cylinder; but the ports where they enter the cylinder have bridges uniting their two sides. The inner and outer walls of the supply-passage are united by connecting-pieces cast therein. An annular exhaust-passage 23 is formed around the outside of the supply-passage 20, said passage communicating directly and continuously with the exhaust-pipe 23^a and subject to the control of valves communicating with the low-pressure cylinder by ports 24 24^a at the ends of said cylinder. Communication between the supply-passage 20 and the high-pressure cylinder 1^a and between the high-pressure and low-pressure cylinders is effected in proper sequence through valve-controlled ports 27 27^a, formed in the wall of the high-pressure cylinder at its upper and its lower ends, respectively. These ports extend completely around the cylinder, but are divided into sections by bridges, as indicated.

As the connection of the two pistons with the oscillating-lever system requires them to work in opposite directions one to the other, the movement of one piston and its rod will

exactly balance that of the other if they are of equal weight.

The form of engine illustrated while more particularly designed for marine or stationary purposes may obviously be applied to use in locomotive-engines or automobiles without variation of its operative principle.

I claim as my invention and desire to secure by Letters Patent—

1. In a fluid-pressure engine, the combination of a pair of cylinders located one within the other, a piston and piston-rod in the inner cylinder, an annular piston and a pair of piston-rods in the outer cylinder, means for constraining the movement of the two pistons in opposite directions to each other, a driving-shaft, a crank thereon, and a main rod coupled at one end to said crank and at the other to the piston-rods of the inner and outer cylinders.

2. In a fluid-pressure engine, the combination of a pair of cylinders located one within the other, a piston and piston-rod in the inner cylinder, an annular piston and a pair of piston-rods in the outer cylinder, a system of oscillating levers forming "parallel motions," connected to the piston-rods and adapted to constrain the piston-rods of the inner and outer cylinders to move in straight lines and in relatively opposite directions, a driving-shaft, a crank thereon, and a main rod connecting the oscillating-lever system with the crank.

3. In a fluid-pressure engine, the combination of a pair of cylinders located one within the other, a piston and piston-rod in the inner cylinder, an annular piston and a pair of piston-rods in the outer cylinder, a system of oscillating levers comprising a primary lever articulated, at one end, to the piston-rod of the inner cylinder and having a movable fulcrum at its opposite end, a pair of primary levers articulated, at one end, to the piston-rods of the outer cylinder and having mov-

able fulcrums at their outer ends, and secondary levers, articulated to the primary levers, and journaled centrally in fixed bearings, a driving-shaft, a crank thereof, and a main rod connecting the oscillating-lever system with the crank.

4. In a fluid-pressure engine, the combination of a pair of cylinders located one within the other, a piston and piston-rod in the inner cylinder, an annular piston and a pair of piston-rods in the outer cylinder, a primary lever articulated at one end to the piston-rod of the inner cylinder, a radial link coupled to said primary lever and to a fixed pivot, a pair of primary levers articulated at one end to the piston-rods of the outer cylinder, radial links coupled to said primary levers and to a fixed pivot, secondary levers, articulated to the primary levers, and journaled centrally in fixed bearings, a driving-shaft, a crank thereon, and a main rod connecting the oscillating-lever system with the crank.

5. In a fluid-pressure engine, the combination of an outer inclosing cylinder, an inner cylinder separate therefrom and detachably connected to one of the heads thereof, an opposite head closing the outer cylinder, a head closing the inner cylinder, a packed joint between the heads and the inner cylinder, a piston and piston-rod in the inner cylinder, an annular piston and a pair of piston-rods in the outer cylinder, a system of oscillating levers forming "parallel motions," connected to the piston-rods and adapted to constrain the piston-rods of the inner and outer cylinders to move in straight lines and in relatively opposite directions, a driving-shaft, a crank thereon, and a main rod connecting the oscillating-lever system with the crank.
